IRONING RACK

Rudolph M. Holly, Riddle, Oreg.

Application June 3, 1954, Serial No. 434,172

1 Claim. (Cl. 211—182)

This invention relates to a movable rack designed primarily for use while ironing apparel, flat work or the like, so that the operator will have a convenient and practical rack for hanging such articles as apparel which are usually hung on coat hangers and placed on a rack, the rack having a convenient shelf for receiving ironed flat work.

An important object of the invention is to provide a movable rack of this character, constructed of a length of light weight material such as aluminum tubing for ease in moving the rack from one location to another, due consideration having been directed to the strength and durability of the rack.

Another important object of the invention is to provide a rack wherein the rear post of the rack is connected with supporting feet which under normal conditions, extend transversely of the base of the stand, but may be moved to a position longitudinally of the horizontal tie rod or base of the rack, thereby permitting the rack to be moved and stored in narrow or restricted places.

With the foregoing and other objects in view which will appear as the description proceeds, the invention consists of certain novel details of construction and combination of parts, hereinafter more fully described and pointed out in the claim, it being understood that changes may be made in the construction and arrangement of parts without departing from the spirit of the invention as claimed.

Referring to the drawings:

Figure 1 is a side elevational view of a rack constructed in accordance with the invention.

Fig. 2 is a front elevational view thereof.

Fig. 3 is a plan view of the rack.

Fig. 4 is a sectional view taken on line 4—4 of Fig. 1.

Fig. 5 is a side elevational view of a modified form of rack.

Fig. 6 is a front elevational view thereof.

Fig. 7 is a plan view of the rack.

Fig. 8 is a sectional view taken on line 8—8 of Fig. 5.

Fig. 9 is a sectional view taken on line 9—9 of Fig. 5.

Fig. 10 is a perspective view of the table used with the form of invention shown by Fig. 5, the view being taken from the bottom.

Referring to the drawings in detail the frame which is indicated generally by the reference character 5, is constructed preferably of a length of aluminum tubing which is bent intermediate its ends to provide a substantially long rear post 6, a forwardly extended horizontal supporting section 7 and a downwardly extended vertical section 8. The tube extends forwardly from the section 8 and provides a horizontal supporting section 9. The front post or leg of the frame being formed integral with the horizontal supporting section 9, extends downwardly at 10, the lower end of the front post 10 being equipped with a caster 11. The reference character 12 indicates a substantially U-shaped foot section which is secured to the lower end of the rear post 6, by means of angles 13 which are bolted to the foot section 12 and the post 6,

2

the foot section 12 extending at right angles to the horizontal supporting section 7, to brace the frame against lateral tilting.

Casters 14 are secured in the lower ends of the foot section 12 to permit the rack to be moved from place to place.

The front and rear posts 10 and 6, are connected by the tie rod 15 which is provided with straps 16 bolted thereto, the straps 16 being tightly secured around the posts to hold the front and rear posts of the frame against slipping, with respect to each other, under the weight of articles supported on the frame.

Secured on the horizontal supporting section 9, is a table 17 held in position by means of the bolts 18, the table providing a support for flat work which may be piled thereon and the flat work held against wrinkling.

In order that the articles of apparel which are hung on the supporting section 7 will be held against sliding from the supporting section 7, screws 20 are secured at the ends of the horizontal supporting section 7, which screws provide stops.

In the form of the invention as shown by Fig. 5 of the drawings, the frame which is indicated generally by the reference character 21, is of practically the same construction as the frame shown in Fig. 1 of the drawings, with the exception that the table indicated by the reference character 22 is secured to the supporting section 9, by means of clamps 23 that are secured to the lower surface of the table 22, the clamps 23 embodying spaced ears 32 which are drawn together around the tubular supporting section 9, by bolts 24 which are extended through aligning openings of the clamps. A notch indicated at 25 is provided in one edge of the table 22 and is adapted to receive a portion of the vertical section 8 of the frame 30 to further secure the table against rotation. Thus it will be seen that due to this construction the bolts which secure the clamps 23 may be loosened allowing the table to be moved from the position shown in full lines in Fig. 5 of the drawings, to the dotted line position, thereby reducing the width of the frame to the minimum.

In this form of the invention, the foot section indicated by the reference character 26 embodies a substantially U-shaped section with a pipe section 27 secured thereto intermediate its ends, the pipe section 27 adapted to be fitted in the open lower end of the rear post of the frame 21, where it is secured in its normal supporting position at right angles with respect to the frame, as shown by Fig. 9 of the drawings. Set screws 28 extend through the rear tubular post of the frame and engage 50 the pipe section 27, securing the foot section 26 against rotation within the rear post of the frame under normal conditions.

Casters 29 extend into the lower ends of the foot section 26 and provide means for supporting the rear portion of the frame. Casters 30 extend into the lower end of the front post sections of the frame and the front and rear post sections of the frame are held in proper spaced relation with each other, by the tie rod 31.

From the foregoing it will be seen that in this form of the invention, not only the table 22 may be swung to the vertical position, but the foot section 26 may be moved to a position parallel with the connecting rod 31 so that the device may be rolled into an exceptionally narrow space for storing.

It will also be seen that I have provided a rack which may be moved into position adjacent an ironing table, so that articles of wearing apparel as well as flat work when ironed, may be placed on the rack or supported thereon to hold them against being wrinkled or mussed.

Having thus described the invention, what is claimed is:

An ironing rack comprising a frame formed of front

and rear vertical posts, said front post being substantially shorter than said rear post, a horizontal bar extending rearwardly from the upper end of said front post, a horizontal bar extending forwardly from the upper end of said rear post, a vertical connecting bar between and integral with said first and second named horizontal bars, a horizontal connecting bar between the lower portions of said posts, a U-shaped clamping member at each end of said horizontal connecting bar and engaging about said posts, means securing the parallel sides of said clamping member to said horizontal connecting bar, an inverted U-shaped foot member, means securing said foot member to the lower end of said rear post, a table, means securing said table to said first named horizontal bar, and

a pair of upstanding pins carried by the upper side of said second named horizontal bar.
